[57] CLAIM

The ornamental design for a traction grille for vehicle, substantially as shown and described.

DESCRIPTION

FIG. 1 is a top perspective view of a traction grille for vehicle showing my new design;

FIG. 2 is a bottom perspective view thereof;

FIG. 3 is a top plan view thereof;

FIG. 4 is a side elevational view thereof, the other side being substantially identical thereto; and

FIG. 5 is a front elevational view thereof, the rear being substantially identical thereto.
